PRINTING TYPE FONT

Anatol Girs, Detroit, Mich.

Application August 31, 1950, Serial No. 12,011

Term of patent 14 years

(Cl. D64—12)

To all whom it may concern:

Be it known that I, Anatol Girs, a citizen of Poland and a resident of the city of Detroit, county of Wayne, State of Michigan, have invented a new, original, and ornamental Design for a Printing Type Font, of which the following is a specification, reference being had to the accompanying drawing, forming a part hereof.

The drawing illustrates face views of a printing type font, showing my new design.

I claim:

The ornamental design for a printing type font, as shown.

ANATOL GIRS.
